UNITED STATES PATENT OFFICE.

LAWRENCE E. BARRINGER, OF SCHENECTADY, NEW YORK, ASSIGNOR TO GENERAL ELECTRIC COMPANY, A CORPORATION OF NEW YORK.

RESISTANCE UNIT.

1,026,377.

Specification of Letters Patent.

Patented May 14, 1912.

Application filed July 14, 1910. Serial No. 571,912.

To all whom it may concern:

Be it known that I, LAWRENCE E. BARRINGER, a citizen of the United States, residing at Schenectady, county of Schenectady, State of New York, have invented certain new and useful Improvements in Resistance Units, of which the following is a specification.

This invention relates to the manufacture 10 of resistance devices for electric circuits and has for its object the provision of an improved device of this character which will be simple and rugged in construction and at the same time thoroughly reliable and 15 efficient.

My invention relates more specifically to resistance units of the type in which a resistance conductor is mounted upon a rigid insulating support so as to form a self- 20 contained unit for use either alone or in connection with other units in various electrical applications.

One way in which resistance units have heretofore been made is by mounting the 25 resistance conductor upon an insulating support, such as porcelain, and cementing it to the support in some manner, as for instance, by means of glaze or enamel. These insulating supports have commonly taken 30 the form of porcelain tubes on the outside of which the resistance conductor is wound. The tube with the wire on it is then dipped in enamel and fired. One of the great difficulties which has been encountered in units 35 thus constructed is the liability of breakage. Porcelain, while being otherwise very well suited for the purpose since it is both fire- 40 proof and water-proof, is nevertheless very brittle and such a tube if dropped will break and completely destroy the unit.

One of the objects of my invention, therefore, is to improve this type of unit by rendering the same strong and rugged, while at the same time preserving the characteristic qualities of the material. In carrying 45 out my invention I strengthen the insulating material by cementing thereto a metallic element. This I do in the case of a porcelain tube by enameling or glazing a metallic tube to the inside of the porcelain tube. A resistance wire is then wound on the tube and coated with enamel and the whole fired so as to unite the parts together and form a rigid structure.

55 In the accompanying drawing disclosing

my invention embodied in concrete form, Figure 1 is a view partly in section of a porcelain tube wound with wire; Fig. 2 is a similar view of the metallic tube coated with enamel; and Fig. 3 is a similar view of 60 the completed resistance unit.

Referring to the drawing, 10 represents an insulating support which I have shown in the form of a porcelain tube having a resistance conductor 11 spirally wound 65 thereon. In order to strengthen this tube mechanically without in any way affecting its electrical properties, I insert a metallic tube 12 within the porcelain tube and cement the two firmly together so as to make 70 a rigid structure. This I do by coating the tube 12 with enamel 13, inserting it in the tube and firing. In order to simplify the process and necessitate only one firing, I wind the tube 11 with a resistance conductor and coat the same with enamel 14. The tube 12 coated with the enamel 13 is inserted within the porcelain tube and the assembled unit fired. The firing fuses the enamel between the iron and porcelain and 75 thereby cements the tubes into a rigid structure and at the same time fuses the enamel on the resistance conductor, thereby cementing the conductor to the porcelain and embedding it in the material, which is refractory and moisture proof. This makes the unit practically indestructible and even if the unit were roughly handled in such a way as to break the porcelain the unit 80 would not be destroyed, since the parts 90 would still adhere together and be ready for service.

It will be understood, of course, that while I have described my invention as being formed in a definite manner with specific materials, I do not limit my invention in these particulars, since various modifications thereof will suggest themselves to those skilled in the art without departing from the spirit of my invention, the scope 95 of which is set forth in the annexed claims.

What I claim as new and desire to secure by Letters Patent of the United States is:

1. A resistance unit comprising a tubular insulating support having a metallic member 105 enameled to the inner surface thereof and a resistance conductor enameled to the outer surface.

2. A resistance unit comprising a support of porcelain and metal enameled to- 110

2
gether and a resistance conductor enameled to the porcelain.

3. A resistance unit comprising a support composed of a porcelain tube having a metal tube enameled to the inner surface thereof and a resistance conductor enameled to the outer surface.

4. The process of making resistance units which consists in mounting a resistance conductor on an insulating support, coating the same with enamel, enameling a metallic member to the support and firing to unite the parts.

5. The process of making resistance units which consists in winding a resistance conductor on an insulating tube, coating the same with enamel, then coating a metallic member with enamel inserting it within the insulating tube, and firing the whole to cement the parts together.

In witness whereof, I have hereunto set my hand this 11th day of July, 1910.

LAWRENCE E. BARRINGER.
